UNITED STATES PATENT OFFICE.

ERNEST HEDENSKOOG, OF MUSKEGON, MICHIGAN, ASSIGNOR TO THE BRUNSWICK-BALKE-COLLENDER CO., OF CHICAGO, ILLINOIS, A CORPORATION OF DELAWARE.

BALL RETARDER FOR BOWLING ALLEYS.

Application filed August 11, 1928. Serial No. 298,995.

My invention relates to bowling alleys and has special relation to devices for retarding the movement of bowling balls on returnways.

5 One object of my invention is to provide a bowling ball retarder which engages the ball and arrests its movement but is actuatable by reason of the weight of the ball to release the same and permit its further movement onto a rack.

Another object of my invention is to provide a retarder of the type described having rails which constitute part of a returnway and cause the moving ball to engage a stop 15 but are movable under the weight of the ball to release the same from the stop and permit the continued movement of the ball.

Further objects and advantages will appear as the description proceeds.

20 Referring to the accompanying drawings: Fig. 1 is a side elevational view of a bowling ball retarder and associated parts embodying my invention.

Figs. 2 and 4 are sectional views on the 25 lines 2—2 and 4—4 of Fig. 1.

Figs. 3 and 5 are sectional views on the lines 3—3 and 5—5 of Fig. 4; and

Fig. 6 is a view partly in elevation and partly in section showing an adapter by 30 means of which the device shown in Figs. 1 to 5 is rendered operable with balls of small diameter.

A pair of rails 1 constitute a part of the returnway on which the balls travel in the 35 direction indicated by an arrow in Fig. 1, and are mounted at one end on a support 2 which extends upwardly thereabove and is bowed outwardly as shown in Fig. 4. A stop or bumper 3, which may be made of 40 soft rubber or other yieldable material, is mounted on the upper part of the support and has a pair of flanges or lateral projections 4 which are slidably received in recesses in the support to permit the stop to 45 be readily assembled in position or withdrawn, so that after one stop becomes worn out another may be readily substituted. A pair of rails 5 which constitute a rack are supported at one end by a newel post 6 and 50 at the other end by the support 2, and the rails 5 are cut away to provide room for a pair of inclined rails 7 which are mounted thereon by means of a pivot pin 8, the

pivoted rails 7 being movable upwardly and downwardly between the rack rails 5. 55

A ball traveling on the rails 1 is brought into engagement with the stop 3 and its movement arrested. The rails 7 then move downwardly under the weight of the ball to release it from the stop and thus to permit 60 the further forward movement thereof. To retard the descent of the rails so that the ball may not move forward too quickly a dashpot is provided which comprises a cylinder 10 having a piston 11 therein through which a 65 duct 12 extends to permit fluid to pass from one face of the piston to the other. A stem 13 secured to the piston extends upwardly through a cap 14 which closes the top of the piston, and the upper end of the stem engages a plate 15 which is secured to the under-face of the rails 7. Because of the smallness of the duct 12 the downward movement of the piston is slow, so that the ball is held motionless for a brief interval of 70 time. When the ball is lowered sufficiently it disengages from the stop 3 and rolls downwardly on the rails 7 and comes to rest on the rack 5.

When the pivoted rails 7 are relieved of 80 the weight of the ball they are moved upwardly by a spring 16 which is enclosed by the cylinder 10 and forces the piston 11 upwardly.

The dashpot also operates to retard the 85 upward movement of the rails 7.

The ball retarder makes very little noise in operation as the movement of the rails 7 is comparatively slow. The retarder, however, is positive in its action and prevents the possibility of a ball passing beyond the stop without having its speed checked.

A mounting is provided for the dashpot, which facilitates the assembly of the latter 95 with the support 2. A lug 17 extends inwardly from a side of the support and constitutes a rest for the base of the cylinder 10. A similar lug 18 has an opening there thru which is aligned with an opening in a 100 horizontal portion 20 of the support, and the cylinder 10 is assembled by merely inserting the same through the aligned openings and bringing the base of the cylinder into engagement with the lug 17.

In order to use the described retarder 105

with balls of small diameter, an adapter is provided as shown in Fig. 6. This comprises a bracket 21 which is detachably secured by means of screws 22 to the upper 5 end of the support 2 and extends downwardly and is interposed between the stop 3 and the free ends of the rails 7. A facing strip 23 of suitable yieldable material extends along the surface of the bracket and 10 is engageable by balls of small diameter traveling upon the returnway. The operation of the retarder with small balls is practically the same as with large balls, the difference being chiefly in the distance of the 15 stop from the rails.

My invention is not limited to the specific details of the constructions illustrated and described, but these constructions may be extensively modified within the spirit of the 20 invention. A substantial range of equivalents is contemplated within the scope of the appended claims.

What I claim as new and desire to secure by Letters Patent is:

- 25 1. In a bowling ball retarder, the combination of a pair of fixed rails constituting a returnway for balls, a stop above said rails engageable by a ball for arresting the movement thereof, and means including a member below said stop and mounted for movement under the weight of the ball for releasing said ball from said stop and permitting the further movement of said ball.
- 30 2. In a bowling ball retarder, the combination of a pair of fixed rails constituting a part of a returnway for a ball, a stop above said returnway for arresting a ball, a pair of movable rails constituting a continuation of the returnway, and means normally sustaining said rails in an elevated position but 35 yieldable under the weight of the ball on said movable rails to permit downward movement of the same and the release of said ball for continued movement.
- 40 3. In a bowling ball retarder, the combination of a pair of fixed rails constituting a part of a returnway for a ball, a stop above said rails, a pair of rails pivoted at one end, and means for normally sustaining the free 45 ends of said rails in an elevated position to cause said ball to engage said stop, but yieldable under the weight of said ball acting on said pivoted rails, said pivoted rails being inclined to permit the continued movement of said ball after its descent beneath said stop.
- 50 4. In a bowling ball retarder, the combination of a pair of fixed rails constituting a part of a returnway, a stop above said fixed rails, a pair of pivoted rails constituting a continuation of said returnway, means for maintaining the free ends of said rails in elevated position adjacent the ends of said fixed rails to cause said ball to engage said 55 stop and be arrested thereby, said means be-

ing yieldable to permit the descent of said pivoted rails under the weight of said ball, and means for retarding the descent of said rails, said rails being inclined downwardly to cause said ball to continue its forward 70 movement after its descent to a point where it is released from said stop.

5. In a bowling ball retarder, the combination of a pair of fixed rails constituting a part of a returnway, a pair of pivoted rails, 75 a stop above the free ends of said pivoted rails for checking the movement of a ball on said returnway, a support for said fixed rails and said stop, and means including a spring housed in said support for normally maintaining said free ends of said pivoted rails in elevated position but yieldable to permit the descent of said pivoted rails and the release of the ball from said stop.

6. In a bowling ball retarder, the combination of a pair of fixed rails, a pair of pivoted rails, all of said rails constituting a returnway, a stop above the free ends of said pivoted rails for checking the movement of a ball on the returnway, a support for said stop and said fixed rails and a dashpot on 90 said support for checking the descent of said pivoted rails under the weight of the ball, said dashpot including a cylinder containing fluid, a piston having a duct there- 95 thru for the passage of fluid from one side of the piston to the other and a stem extending upwardly from said piston and operatively related to said pivoted rails adjacent their free ends, and a spring in said cylinder 100 for forcing said piston upwardly and normally maintaining the free ends of said pivoted rails in elevated position whereby a ball traveling on the returnway is checked by engaging said stop, said spring being 105 yieldable to permit the descent of said pivoted rails and the release of said ball from said stop.

7. In a bowling ball retarder, the combination of a pair of fixed rails constituting a 110 part of a returnway, a newel post, a pair of rails constituting a rack for balls and rigidly secured at one end about said newel post, a support for the other ends of the rack rails and said fixed rails, a pair of rails 115 pivoted to said rack rails, means for normally maintaining the free ends of said pivoted rails adjacent the ends of said fixed rails so as to constitute a continuation of the returnway, a stop above said free ends for arresting the movement of a ball on the returnway, and means being yieldable under the weight of a ball on said pivoted rails to permit them to descend and release said ball from said stop.

8. In a bowling ball retarder, the combination of a pair of fixed rails constituting a part of a returnway, a pair of movable rails, 120 a stop, a support holding said stop above said movable rails in position to be engaged 125

by a large ball traveling on said returnway and an additional stop detachably secured to said support and positioned between the first-mentioned stop and the returnway and 5 engageable by a small ball traveling on the returnway, and means normally supporting said movable rails in elevated position but yieldable under the weight of a ball on said movable rails to permit the ball to move forward under the stops and become disengaged 10 therefrom.

In testimony whereof I hereunto subscribe my name.

ERNEST HEDENSKOOG.
